DOOR CASING

Filed March 19, 1923

UNITED STATES PATENT OFFICE.

WILLIAM N. DAVIS, OF DETROIT, MICHIGAN, ASSIGNOR TO GENERAL MOTORS CORPORATION, OF DETROIT, MICHIGAN, A CORPORATION OF DELAWARE.

DOOR CASING.

Application filed March 19, 1923. Serial No. 626,058.

To all whom it may concern:

Be it known that I, WILLIAM N. DAVIS, a citizen of the United States, and a resident of Detroit, county of Wayne, and State of Michigan, have invented certain new and useful Improvements in Door Casings, of which the following is a full, clear, concise, and exact description, such as will enable others skilled in the art to which the invention relates to make and use the same, reference being made therein to the accompanying drawings, which form a part of this specification.

This invention relates to door casings, and is illustrated as embodied in an automobile. An object of the invention is to provide a structure which will be durable under the hard service given automobile doors and their casings, and which at the same time 20 can be readily and inexpensively manufactured.

With this object in view, the invention contemplates bending a piece of sheet metal to provide a channel-shaped jamb portion, 25 and preferably also a flange to serve as a facing for the edge of the doorpost which supports the door casing. According to one desirable construction, the channel portion is provided with a hiatus or gap which, in 30 connection with a striker plate, provides a recess for the latch.

Of especial utility in a casing of this sort is a construction in which a jamb member is provided with a recess, as by cutting 35 an opening in the above-described channel portion, and an adjustable holder for a resilient block or door bumper is slidably arranged in the recess. To facilitate adjusting the holder, means may be provided for 40 moving it back and forth, as by arranging a screw through the back of the channel portion and threading it into a hole in the bottom of the holder. It adds to the appearance of such a construction to arrange 45 the head of the screw so that it is concealed by the ornamental facing along the inner side of the door casing.

The above and other features and objects of the invention, including various novel 50 combinations and desirable specific con-

struction, will be apparent from the following description of the illustrative embodiment of the invention shown in the accompanying drawings, in which:

Figure 1 is a side elevation of the door 55 casing;

Figure 2 is an end elevation thereof, partly broken away;

Figure 3 is a section on the line 3—3 of Figure 2, but showing the door closed and 60 latched;

Figure 4 is a section on the line 4—4 of Figure 2, showing the latch receiving recess;

Figure 5 is a section on the line 5—5 of Figure 2, showing the door bumper; 65

Figure 6 is a section on the line 6—6 of Figure 5, also showing the bumper, and

Figure 7 is a view, corresponding to Figure 4, of a modification.

In the form shown in the drawings, the 70 body of an automobile, includes an upright door post 10 which serves as a support for a jamb member 12, bent from sheet metal to provide a channel portion 14, which forms a seat against which door 16 closes, and 75 preferably also a flange 18 which forms a facing for the edge of post 10. The channel portion overlaps the inner side of the post, as shown in Figs. 3 and 5, and is secured thereto by fastenings such as screws, and 80 similarly flange 18 is secured to the post 10. Alining members 20 are mounted in the jamb member 12 by cutting away the front face of the channel portion, in position to 85 engage opposite sides of an alining member carried by door 16.

The invention contemplates forming a recess for latch 22 of door 16, in a novel manner, by flattening down a portion 24 of the metal substantially into the plane of 90 flange 18, to form a bottom wall for a gap or hiatus in the channel portion 14. A striker plate 26 may then be secured to post 10 by screws 28 passing through lugs on its opposite ends, and through flange 18, into 95 post 10. As the channel portion 14 is discontinuous, and as the striker plate 26 is opposite the gap therein, the striker plate does not extend at any point into the channel portion, and may thus be assembled with 100

great facility. The gap formed as described above, and the striker plate, together define a recess for latch 22. The portion 24 may be flattened down in a number of different ways, within the scope of my invention, as by a die-shaping or crushing operation (Figure 4), which has the advantage of providing side walls for the latch-receiving recess, or by cutting through the metal at spaced points to provide a tongue which is bent down into place (Figure 7), this method providing sharp corners for the recess.

To regard this same subject-matter from a slightly different point of view, it may be said that there are two aligned channel portions 14 separated by a latch receiving gap having a bottom wall 24 which, in the form shown in Figure 4, serves to connect them.

According to another feature of the invention, door 16 is engaged by bumpers comprising resilient blocks 30 of rubber or similar material, mounted in holders 32 which are arranged to grasp the blocks by their sides, and which are shouldered to engage the outer face of channel portion 14. The holders are slidably arranged in recesses formed in the jamb member by cutting openings in the channel portion, and are arranged to be adjusted to take up for wear or inequalities in blocks 30 by turning screws 34 threaded through openings in the bottoms of the holders. Screws 34 are held against longitudinal movement by washers 36 keyed thereto, and by engagement of their heads with the inner face of flange portion 14, where the heads are readily accessible.

For the sake of neatness of appearance, I prefer that the usual ornamental facing or piping 38 be arranged to cover the inner edge of the jamb member and the heads of screws 34. Holes 40 may be cut in the facing if desired, to permit adjustment of the screws after the facing is in place.

The advantages of a unitary jamb member such as described, together with the novel latch-receiving recess and the improved bumpers, will be obvious, and while one illustrative construction has been described, it is not my intention to limit the scope of the invention to that particular construction or otherwise than by the terms of the appended claims.

55 I claim:

1. A door casing comprising a sheet-metal jamb member bent to have a channel portion to form a seat for a door and which channel portion is provided with a gap, and a striker plate cooperating with said gap to define a latch-receiving recess.

2. A door casing comprising a sheet-metal jamb member bent to have a channel portion to form a seat for a door, part of the channel portion being flattened down to provide a

gap or hiatus therein constructed and arranged to cooperate with a striker plate to define a latch-receiving recess.

3. A door casing comprising a sheet-metal jamb member bent to have a channel portion 70 to form a seat for a door, part of the channel portion being flattened down into a plane substantially parallel to the top face of the channel portion to form a bottom wall for a latch-receiving recess.

4. A door casing comprising a sheet-metal jamb member bent to have two aligned door engaging channel portions separated by a latch-receiving gap having a bottom wall.

5. A door casing comprising a sheet metal 80 jamb member bent to have a channel portion to form a seat for a door and an adjacent facing flange for a door post, part of the channel portion being flattened down into the plane of the flange, to cooperate with a 85 striker plate mounted on the flange to define a latch-receiving recess.

6. A door casing comprising, in combination, a sheet-metal jamb member bent to have a channel portion and an adjacent facing 90 flange, the channel portion being cut away to define an opening, a holder containing a resilient block and arranged in the opening slidably engaging the edges of the opening and slidably engaging the flange, the holder being shouldered to engage the face of the channel portion, an adjusting screw threaded 95 into a hole in the bottom of the holder and having its head accessible from the opposite face of the channel portion, and means for holding the screw against longitudinal movement in the channel portion.

7. A door casing comprising, in combination, a sheet-metal jamb member bent to have a channel portion and an adjacent facing flange, the channel portion being cut away to define an opening, a holder containing a resilient block and arranged in the opening slidably engaging the edges of the opening and slidably engaging the flange, 105 and a screw for adjusting the holder to advance said block.

8. A door casing comprising, in combination, a sheet-metal jamb member bent to have a channel portion and an adjacent facing flange, the channel portion being cut away to define an opening, a holder containing a resilient block and arranged in the opening slidably engaging the edges of the opening and slidably engaging the flange, 115 and means for adjusting the holder to advance said block.

9. A door casing comprising, in combination, a channel-shaped metal jamb member having openings cut in the face directed 125 toward the door, a holder containing a resilient block arranged in each opening, and means for moving the holders backward or forward in the openings to adjust the positions of the blocks.

10. A door casing comprising, in combination, a jamb member having a recess, a shouldered holder in the recess containing a resilient block and arranged slidably to engage 5 the sides of the recess, and an adjusting screw engaging the holder and operable from outside the casing to advance said block.

11. A door casing comprising, in combination, a jamb member having a recess, a 10 holder slidable in the recess and having a threaded opening in its bottom, a resilient block carried by the holder, and a block adjusting screw passing through said member and threaded into the hole of the 15 slideable holder.

12. A door casing comprising, in combination, a jamb member having a recess, a holder in the recess formed to grasp by its sides a resilient block and having a threaded 20 hole through its bottom, and a block-adjust-

ing screw held against longitudinal movement in said member and threaded into the hole through the holder.

13. A door casing comprising, in combination, a jamb member having a recess, a 25 holder in the recess formed to grasp by its sides a resilient block and having a threaded hole through its bottom, a headed block-adjusting screw passing through said member into the threaded hole and held against 30 longitudinal movement in said member, and an ornamental facing arranged to conceal the head of said screw.

14. A door casing comprising, in combination, a jamb member, bumpers carried 35 thereby, an ornamental facing therefor, and bumper-adjusting means beneath and concealed by said facing.

In testimony whereof I affix my signature.

WILLIAM N. DAVIS.
